UNITED STATES PATENT OFFICE.

HARCOURT W. BULL, OF SPRINGFIELD, MASSACHUSETTS.

PRINTING-TELEGRAPH.

No. 923,423.

Specification of Letters Patent.

Patented June 1, 1902.

Application filed April 17, 1902. Serial No. 427,612.

To all whom it may concern:

Be it known that I, HARCOURT W. BULL, a citizen of the United States of America, residing at Springfield, in the county of Hampden and State of Massachusetts, have invented new and useful Improvements in Printing-Telegraphs, of which the following is a specification.

This invention relates to improvements in printing telegraph systems and it has for its object to provide a transmitting and receiving device, the transmitting device comprising in general a constantly rotating cylinder, a series of keys adapted to engage the cylinder, to make and break the main line circuit in accordance with the particular letter or character that is being transmitted. The receiving end of the line includes, in general, a rotating cylinder provided with devices for actuating a series of printing levers, whereby when said levers are actuated the letters are printed in page form on a sheet of paper which is actuated by any suitable mechanism.

Further details of the object and nature of the invention will be stated in the specification and shown in the drawings forming a part thereof and particularly pointed out in the claims.

In the drawings forming part of this application,—Figure 1 is a transverse sectional view on the line 1—1 of Fig. 2, the key lever mechanism being shown in side elevation. Fig. 2 is a general diagrammatic view of the system as a whole, while Fig. 3 is a detailed plan view of the trailing lever construction whereby the same is held either in engagement with, or disengaged from, the sending cylinder. Fig. 4 is a detail sectional view on the line 4—4 of Fig. 3, showing the spring fingers for holding the trailing lever in contact with, or disengaged from, the sending cylinder. Fig. 5 is a modification showing means for moving the receiving cylinder transversely, and Fig. 6 is a detail view of the movable bearing block in which is mounted the shaft of the receiving cylinder on the line 6—6 of Fig. 5.

Referring to the drawings in detail, *a* designates a cylinder made of some suitable insulating material, as hard rubber, that is mounted for rotation in the bearings *b* and *c*, the shaft *d* thereof being connected to a suitable motive power *e*,—preferably a spring motor,—although I do not limit myself to

any special kind of motor. Inlaid in the surface of the cylinder *a* are the metallic contact blocks or pieces *f* which are so arranged circumferentially with relation to each other as to form the letters of the alphabet, as for example the two blocks at the left of Fig. 2, (designated by the letters *g* and *h*) stand for the letters "a" and "b".

i designates a standard that is secured to the base-piece *j* and has pivotally mounted in the upper end thereof a trailing lever *k* that is pivoted at the point *m*. *n* designates another standard secured to the base-piece *j* and has pivotally mounted in the upper end thereof a key-lever *o*, at the point *p*. This lever is normally drawn downward toward the base-piece *j* at its inner end by means of a light spring *q*. The standard *i* has secured to its inner side a bracket *r* to which are secured on opposite sides thereof spring fingers *s* and *s'* to hold the trailing lever *k* in contact either with or away from, the sending roller *a*. When the key-lever *o* is depressed, the inner end of the trailing lever *k* is brought into contact with the transmitting roller *a*, whereby an electrical impulse is sent over the line *t* as its inner end passes over the blocks *g* or *h*, the current flowing from the battery *u* to the shaft *v* on which the levers *k* are pivoted; then through the trailing levers *k* to the contact-blocks, and from there to the shaft *d* which is connected to the line *t*, as shown; and as the lever engages the contact-blocks in succession, the current will be made and broken on the line in accordance with the letter or character that is to be transmitted, as readily understood. When the trailing-lever *k* reaches the end of the contact-block, as for instance *g*, its inner end engages a projection *w* causing the same to be elevated clear of the rotating cylinder *a* to its initial position and thus prevent a repetition of the signal without depressing the transmitting key a second time.

Referring now to the receiving station of the apparatus: *x* designates a rotating cylinder provided with a series of projections *y* that are arranged in spiral relation on the surface of the cylinder *x* which is connected, by means of the shaft *z*, to the motive power *2* which is preferably a spring motor and is of the same construction as that referred to above in connection with the motive power for the cylinder *a*. These two motors

are designed to rotate at the same speed so that each cylinder will be moved through the same arc at equal times.

3 designates an electro-magnet of the horse-shoe type that is connected to the line *t* so that the same is energized as each impulse of current is sent over the line.

4 designates a piece of soft iron that is secured to the end of the rotating cylinder 10 *x* and serves as an armature for the electro-magnet 3, whereby the cylinder *x* will be drawn laterally toward the pole-pieces of the electro-magnet at each energization of the same. In order to permit a lateral movement of the cylinder *x*, the shaft *z* is provided with a pin 5 which engages slots 6 in the cylinder *x* and at the same time causes the cylinder *x* to be driven from the shaft *z*. A spring 7 has one end attached to the cylinder *x* and its other end to the shaft *z* whereby the cylinder is constantly drawn away from the electro-magnets 3 and into engagement with the stops 8 that are carried by the shaft *z*. In order to prevent the armature sticking to the pole-pieces of the electro-magnet, a pin 9 is carried by the shaft *z*.

10 designates a series of printing levers that are pivotally mounted on the shaft 11 which is carried by suitable standards 12.

13 designates a sheet of paper that is moved laterally and longitudinally by any suitable mechanism well known in the type-writing art so that the message, when received will be printed thereon in page form.

In the normal operation of the cylinder *x*, the inner ends of the printing levers 10 will pass between the projections *y*, but when the impulse which produces a letter or character 40 is transmitted over the line, the lateral movement of the cylinder, as described, will take place when a projection *y* engages the inner end of the printing lever to effect the printing of the desired character or letter on the sheet 45 of paper 13. The spiral arrangement of the projections *y* is for the purpose of permitting the impulse, which produces a character, to be transmitted without effecting the printing of a wrong character. It should be stated 50 that the rotation of the cylinder *x* is so timed that the character will not be printed until after the impulse of which the character is composed is transmitted over the line.

I have not described any specific means 55 for simultaneously starting and stopping the motors *s* and 2 which drive the cylinders *a* and *x* in unison, as this feature, which relates to synchronizing devices, is old in the art of printing telegraphs and need not be referred 60 to here in detail. The essential feature of my invention lies in the lateral or axial movement of the receiving cylinder *x* by which the electro-magnet 3 is energized by the line current, whereby the printing is effected by the 65 printing levers, as described.

I do not limit myself to the means shown for effecting the printing, as I may provide an alternate arrangement for effecting the lateral movement of the levers 10 instead of the cylinder *x*. Neither do I limit myself to the employment of any particular code, but if desired an ordinary Morse sounder may be substituted for the receiving mechanism shown.

I do not limit myself to the arrangement of contact blocks on the transmitting cylinder *a*, as I prefer to arrange them in spiral form, as shown.

Referring now to the modification shown in Fig. 5, the transmitting and receiving cylinders are the same in construction as already described. The receiving cylinder 14 is mounted in the slideable bearing blocks 15 on the guide or track-way 16. 17 designates a post to which is connected a spring 18 normally under tension for holding the bearing blocks 15 rearwardly toward the stops 19, the spring having its other end connected to a post 20 on the bearing blocks 15. 21 designates two electro-magnets that are mounted on the guide or track-ways 16 and are connected to the line circuit *t* by means of the wires 22 and 23. This connection is made in parallel arrangement with the line and ground which is indicated at 24. The purpose of this parallel connection is such that at every electrical impulse over the line *t* both magnets will be simultaneously energized and the cylinder 14 thereby drawn forward toward the printing levers 10. The inner ends of the printing levers will then be struck by the elevated blocks *y* and the printing effected. In order to permit the cylinder 14 to be readily drawn forward by the magnets 21, the shaft thereon is connected to the motor 2 by means of the flexible shaft 25. After the letter is printed and the electrical impulse ceases to hold the receiving cylinder forward, the springs 18 will immediately pull the cylinder back again against the stops 19.

What I claim, is:—

1. In combination with a transmitting cylinder of a printing telegraph apparatus, a series of key-levers, a series of trailing levers operable from the key-levers for moving the trailing levers into engagement with the transmitting cylinder, the transmitting cylinder being provided with contact pieces representing the letters of the alphabet, a line circuit, a receiving cylinder, a series of projections secured to the receiving cylinder, a series of printing levers arranged so that their inner ends normally pass the series of projections, and means under the control of the line circuit for moving the receiving cylinder so that the projections thereon will engage the printing levers to print the letter corresponding to the transmitted letter, a source of electrical energy, and electrical connections be-

- tween the source of electrical energy and the line circuit.
2. An apparatus of the class described, a line circuit, an electro magnet included therein, a receiving cylinder, an armature carried thereby, means for transmitting electrical impulses over the line, and means for permitting the receiving cylinder to be moved by the electro magnet at each impulse, to effect the printing of the desired character, or letter, as described.
3. A printing telegraph system comprising a transmitting cylinder and a receiving cylinder, electrical connections between said cylinders and including an electro magnet therein, said electro magnet being arranged to move the receiving cylinder through a predetermined distance upon the transmission of electrical impulses over the line, and means carried by the receiving cylinder to effect the printing of the transmitted characters.
4. A printing telegraph system having, in combination, with the receiving cylinder thereof, a line circuit, a transmitting cylinder, a series of contact pieces carried by the transmitting cylinder, a series of levers for making the line circuit, projections located adjacent the contact-pieces representing the characters to be transmitted for breaking the circuit, whereby when the impulses representing the characters are transmitted, said projections will disengage the levers from contact with the transmitting cylinder, and means for effecting the printing of the transmitted characters at the receiving end of the line.
5. A printing telegraph system having in combination a transmitting cylinder, a receiving cylinder, means for rotating said cylinders in unison, means for effecting the movement of the receiving cylinder at each transmission of an electrical impulse over the line circuit, said means including an electro magnetic apparatus for effecting movement of the receiving cylinder, as described.
6. In an apparatus of the class described, a line circuit, an electro magnet included therein, a receiving cylinder, an armature carried thereby, means for transmitting electrical impulses over the line, and means for permitting the receiving cylinder to be axially moved by the electro magnet at each impulse, to effect the printing of the desired character or letter, as described.
